METHOD OF TREATING A PRODUCING FORMATION

Robert E. Lee, Coleman, Tex., assignor to Lee
Angular Drill Corporation, Dallas, Tex., a cor-
poration of Delaware

Application February 23, 1937, Serial No. 127,028

3 Claims. (Cl. 166—21)

This invention relates to a method of chemically treating, shooting and repressuring wells and it has particular reference to a method which provides for specifically locating the acid or other chemical, explosive charges and other effective agents in and about the bottom of the hole.

The principal object of the invention is to provide first: the step of boring a hole in the earth; second, the step of enlarging the communicating area of the bore hole at its bottom by providing a series of radial or annular channels from the axis of the bore hole into the formation adjacent the bore hole at various levels; third, in packing off selective groups of channels at predetermined levels and in charging said selective groups of channels with a prescribed medium such as acid or other chemicals, explosive charges, water, gas or the like, for the purpose of renewing or increasing the flow of liquid from the well.

Yet another object of the invention is to provide a method, which includes the step of channeling and treatment, for replenishing the natural pressure medium in oil and gas producing formations where such medium has been exhausted or diminished, over wide areas, by excessive withdrawals of this necessary prerequisite to production.

Broadly, the invention anticipates a method for drilling wells which includes the step of angularly drilling at the bottom of the hole to enlarge the productive area of the well and which step shall include the drilling of angular channels as a continuation of the first step of boring the initial hole, as well as channeling wells whose production has ceased or diminished. Also, the invention is effective, through the step of introducing chemicals, explosive charges, water, gas and the like, into said channels, in further increasing the production since to introduce acid in the channels, a more extensive and uniform drainage area of the formation is effected than could be obtained by present methods, where only the length of the bore hole wall is affected.

With the foregoing objects as paramount, the invention will be seen as possessing other salient features and novel steps of the method herein-described and illustrated in the accompanying drawing, wherein:—

Figure 1 is a vertical section through a well showing the angular channels and means for introducing acid or other medium into the channels.

Figure 2 is a section on lines 2—2 on Figure 1, and

Figure 2 illustrates a means for packing off selective channels at predetermined elevations.

Continuing with a more detailed description of the invention, reference is primarily made to Figure 1 which shows the conventional well casing 1, in which is disposed the conventional tubing 2, both being in vertical section.

The present invention defines an improvement over the claims of my Patent No. 1,816,260 in that in this patent, repressuring of wells is effected and is obtained by recirculation of a repressuring medium through upper and lower angular or lateral channels and out of the well through a discharge pipe or tubing. This invention seeks to define a method for acidizing, shooting or re-pressuring wells where the effectiveness of these operations depends upon channeling or otherwise increasing the flow of liquid from a well, without recirculation. Accordingly, the first step of the present invention comprises the step of drilling 20 the well and then in drilling the series of channels 3, after which the vertical bore or well is deepened and another group of angular channels or openings 4 are drilled at a level below that of the first group 3. The casing 1 is set in the 25 usual manner and the tubing 2 is run to a point below the terminal of the casing, and is provided with a series of apertures, windows or perforations 5.

A liquid or fluid medium such as acid or other chemical, water or gas is introduced by gravity or pressure by means of a pump 6, (Figure 3) through the line 7, into the tubing 2, into the well and upon reaching the bottom of the bore hole, the medium flows into the lateral or angular channels 3 and 4, where it acts upon or affects the formation according to the purpose intended therefor.

In order, however, to place an explosive charge in one, several or all of the channels 3 and 4, the 40 tubing 2 is required to be withdrawn so that a liquefied or solidified explosive charge may be lowered and directed into the channel or channels to be thus treated, in a uniform manner, after which the charge is set off.

When it is desired to treat or acidize channels at a predetermined level, the expansion packer 8, such as shown in Figure 3 is provided and may be of the conventional self expansion design. 50 This packer is so disposed on the tubing string 9 that when the tubing extension 10 is set down upon the bottom of the hole 11, it expands against the walls of the hole to separate the upper channel group 12 from the lower channel group 13. 55

A shoe 14 is provided upon the lower end of the pipe string 10, as shown.

Accordingly, when the shoe 14 reaches the bottom of the hole 11, and the weight of the string expands the packer 8, closing the hole against passage of the treating medium to the lower channels 13, only the upper series of channels 12 receive the treating medium which is passed downward by gravity or pressure of pump 6, through pipe 15, and ports 16 in the reversible joint 17, and into the upper series of channels 12, without affecting the lower series of channels 13.

It will be observed that the joint 17 is threaded onto the lower end of the tubing string in Figure 3. This feature enables the joint to be inverted and threaded onto the bottom of the packer 8, so that the ports 16 will be exposed to the lower series of channels 13 and in order that the treating medium will not rise in the hole, and flow into the upper series of channels 12 when it is desired to treat the lower series. It will be understood that the pipe string is removed from the bore hole after treating a group of channels preparatory to inverting the joint 17 for treating another group of channels.

Thus, the groups of channels may be treated collectively or separately, as required by employing the packer or dispensing with it entirely as shown in Figure 1.

A distinct advantage, however, in using the packer lies in the fact that the upper series of channels 12 may be acidulated to dissolve calcareous substance, limy and other formations detrimental to fluid flow, after which a pressure medium is forced into the lower series of channels and which latter medium will be effective to expel dissolved matter from the treated channels and out of the drainage area of the bore hole. This operation may be inversely applied, as apparent.

It is apparent from the foregoing that productive areas of wells and entire fields where salt water and other natural pressure mediums have been depleted, may again be made productive by the present method which has been successfully practiced over a wide area of oil and gas producing regions.

Also, in the art of geophysical prospecting, explosive charges are placed in bore holes in predetermined spaced relationship, exploded and the resulting waves seismographically intercepted and recorded. The present invention affords an ad-

vantage in this practice in that shots may be uniformly placed in the angular channels and the vertical bore hole suitably plugged to prevent interference by the objectionable ground waves when the charges are exploded on or near the earth's surface. Thus, a more intelligible and comprehensive record of the tectonics of the earth may be obtained.

Manifestly, the construction of the apparatus and the steps of the method described herein are capable of considerable modification and such modification as is considered within the scope and meaning of the appended claims is also considered within the spirit and intent of the invention.

What is claimed is:

1. The method of acidizing petroleum producing formations which consists initially in boring a vertical hole, then in drilling a plurality of angular openings at predetermined levels and angles from and with respect to the vertical bore hole, in packing off selective groups of said openings, in introducing into unrestricted groups of openings an acidizing agent through said bore hole, in changing the position of the discharge point of said agent with respect to the packing to obtain access to companion groups of openings and in introducing therewith said acidizing agent.

2. The method of acidizing, chemically treating and repressuring a petroleum producing earth formation, characterized by boring a hole into said formation and in drilling a plurality of angular openings at predetermined levels and angles from the bore hole, in packing off selective groups of said openings, in introducing into the unrestricted groups of openings a treating reagent through said bore hole, in changing the discharge point of the reagent with respect to the packing to effect ingress into the formation to adjacent groups of openings, and in impressing fluid pressure upon the treating reagent.

3. The method of increasing the porosity and productivity of an oil and gas producing formation characterized by drilling vertically into said formation, in drilling angular openings into said formation at substantially right angles to the axis of the vertical bore hole and at vertically spaced intervals, in enclosing the openings at selected levels, in introducing acid into said angular openings, and in changing the position of the discharge point of said acid with respect to the packing to obtain access to companion groups of openings.

ROBERT E. LEE.
